GOLF CLUB

Harold A. Thomas, Murrysville, Pa., assignor to
Harvey L. Hensel, Frankfort, Mich.

Filed Aug. 20, 1970, Ser. No. 24,611

Term of patent 14 years

Int. Cl. D21—02

U.S. Cl. D34—5

FIG. 1 is a side elevational view of a golf club showing my novel design;

FIG. 2 is an enlarged fragmentary front elevational view;

FIG. 3 is a rear elevational view of FIG. 2;

FIG. 4 is a top plan view thereof; and

FIG. 5 is a bottom plan thereof.

I claim:

The ornamental design for a golf club, as shown.
